UNITED STATES PATENT OFFICE

ARTHUR WILLIAM NAUS, OF NEW YORK, N. Y.

BUCKLE

Application filed February 27, 1931. Serial No. 518,657.

My invention relates to a new and improved form of buckle suitable for fastening to slippers or shoes, dresses, hats, and the like.

Devices of this character which have heretofore comprised two separable elements, the elements have been joined together in such a way that there was a catch, or hook, or hasp, or other contrivance protruding beyond the rear surface of the buckle. Such arrangements are undesirable for a number of reasons. The projection may press against the part of the body where the buckle is being used and thus irritate or injure the flesh at that point. The projection provides a ready source for engaging the threads of fabrics next to which the buckle may be located, and thus tear and injure the fabric. This is especially true in the case of a slipper buckle, where the inside of the buckle may be resting against the silk hose, and the catching of a thread will start a "run" or unravelling.

It is therefore one object of my invention to provide a separable buckle of the above indicated character wherein it is unnecessary to have any projections beyond the rear surface thereof, so that all of the above objections are at once eliminated.

It is another object of my invention to provide a buckle of the above indicated character wherein the parts when assembled are firmly and securely held together without the aid of special locking means.

It is another object of my invention to provide a buckle of the above indicated character wherein the separable members are joined together without the necessity of a special movement of either member, such as twisting or sliding in order to position the two parts in proper cooperative position.

My invention is shown as applied to a buckle comprising two jeweled parts. The jewel carriers are embedded or received in a frame or mounting of a character to complete and carry out the artistic nature of the buckle.

The objects of my invention are accomplished by providing separate jewel carriers, each of which carries the mounting frame

for the other jewel carrier. One of the mounting frames is provided with an aperture wide enough to permit the passage of the jewel carrier therethrough, and of depth enough that no special movement of the parts is necessary to properly locate the two jewel carriers in their respective frames.

Other and further objects of my invention will be apparent from the following specification taken in conjunction with the accompanying drawings, wherein

Figure 1 is a plan view of one form of my improved buckle in assembled position;

Figs. 2 and 3 are enlarged plan views respectively of the separate elements of my improved buckle;

Figs. 4 and 5 are respectively central vertical sections of the separate parts shown in Figs. 2 and 3;

Fig. 6 is a central vertical section of my improved buckle showing the parts in assembled position;

Fig. 7 is a vertical cross section on the lines 7—7 of Fig. 6; and

Fig. 8 is a vertical cross section on the lines 8—8 of Fig. 6.

Referring to Figs. 3 and 5 of the drawings, there is illustrated one-half of my improved buckle. It comprises a jewel carrier 11 in which is mounted a jewel 12. The jewel carrier 11 is connected to a mounting frame 13 having a depressed portion 14 and a rim 15 which is beaded or otherwise ornamented as indicated at 16 to conform to the artistic creation or design of the buckle. The jewel carrier 11 and frame 13 are connected together by a throat 17. The rim 15 is cut away as indicated at 18 adjacent the throat 17 and this cut away portion is of the same depth as of the depression 14. Likewise the throat 17 is on the same surface level as the cut away portion 18 and depression 14. It will be noted that the rear of the jewel carrier 11 is provided with a cut away portion 19, the purpose of which will be referred to hereinafter.

Referring to Figs. 2 and 4, there is shown the other half of my improved buckle. Here there is a jewel carrier 21 in which a jewel 22 is mounted. The jewel carrier 21 is joined to a mounting frame 23 by means of a throat

24. The frame 23 comprises a depression 25 and a surrounding frame 26 which is likewise beaded or otherwise decorated as indicated at 27, to carry out the artistic design of the buckle.

25. The frame 26 is continuous. The throat 24 carries a beaded section 28 which is a continuation of a beaded section 16 of the mounting frame 13 (Fig. 3) and this section 28 is intended, as will be hereinafter described, to exactly fit into the cut away portion 18 referred to in Figs. 3 and 5, and thus complete the rim 15 of the other half of the buckle.

26. Referring again to Figs. 2 and 4, it will be noted that there is an opening 29 extending through from the back of the frame 23. This opening extends through the mounting frame 23 and is of the same width as the depression 25 at its widest point. The opening also extends laterally for one-half of the depression 25. The under surface of the mounting frame 23 is cut away as indicated at 31 to form an opening similar to the opening 18 of Fig. 3, except that in the case of the member shown in Figs. 2 and 4, the opening is on the under surface of the mounting frame 23. The opening 31 will receive the throat 17.

27. It should be pointed out that the jewel carriers 11 and 21 are of the same dimensions and that the depressions 14 and 25 are likewise of the proper dimensions to receive the jewel carriers 11 and 21, and that the jewel carriers are, in the design shown in these drawings, embedded within and flush with the top of the surrounding mounting frame.

28. To insert the two halves of my improved buckle together, it is merely necessary to pass the jewel carrier 11 through the opening 29 and cause the cut away portion 19 under the jewel carrier 11 to seat upon the base 32 of the depression 25 for the mounting frame 23. This simple bringing together of the parts will cause the jewel carriers 11 and 21 to seat in their respective mounting frames 23 and 13 because the cut away portions 18 and 31 will receive the throats 24 and 17 respectively. The throats engaging in the cut away portions 18 and 31 securely hold the parts from vertical movement, and the fitting of the carriers 11 and 21 in the depressions of the frames holds the two parts from longitudinal movement. This is clearly shown in Figs. 6, 7 and 8, which are sectional views of the two halves in assembled position.

29. It will also be apparent that if the jewel carriers are made of a size so as to closely and exactly fit the interior of the depressions 14 and 25 so that a slight pressure may have to be exerted to push them in place, there will be a further firm securing of the members together.

30. Attention is called to Fig. 6, where it will be noted that in the assembled form the rear surface of the two halves are flush and form

a continuous line across the entire assembled buckle. It will also be noticed that the rear surface is arched as indicated at 33 which in the case of certain applications may be desirable.

31. It is apparent that means for securing the buckle to the belt or slippers or other garment may be located at any convenient place and with due consideration for the ornamental character of the buckle. In the form shown in the drawings, I have indicated a pair of straps, or stirrups, or eyes 34, 35, respectively mounted on the rear surface of the mounting frames 23 and 13. The use of these in enabling a buckle to be secured in the position it is to be worn in is well known. It is to be noted that the drawings here show a slipper or garter buckle and attention is called to the fact that except for the presence of the stirrups 34, 35, on the back of these buckles the rear surface of the buckle is maintained smooth and free of obstructions.

32. The elastic, or other material to which the buckle is to be applied, is secured to these straps or stirrups and all of the rest of the rear surface of the buckle is clear and free of all projections and obstructions of any character. Hence, there is nothing there to injure the flesh or damage the stockings.

33. From the foregoing description it will be apparent that I have provided a simple and efficient arrangement of joining together the two halves of buckles without destroying the artistic or ornamental character of the buckle, and without the necessity of any special manner of twisting or otherwise locking or securing the two halves together. At the same time my improved buckle provides a firm and rigid body structure.

34. Modifications may be made in the arrangement and location of parts within the spirit and scope of my invention, and such modifications are intended to be covered by the appended claims.

35. I claim:

36. 1. A buckle having two separable members each comprising a mounting frame and an element to be mounted in a frame, each frame and element being joined together by a throat, and each of said members having a mounting stirrup thereon, one of said members having a slot therethrough of a width to receive the element of the other member whereby the respective frames and elements may be assembled together with said elements mounted in said frames.

37. 2. A buckle having two separable members each comprising a mounting frame and an element to be mounted in a frame, each frame and element being joined together by a throat, one of said members having a slot therein of a width to receive the element of the other member whereby the respective frames and elements may be assembled together, one

member having a cut-away portion adjacent the throat and located on top of its member, and the opposite member having a cut-away portion adjacent the throat and located under its member, whereby when the two members are interfitted they are firmly held in assembled position.

3. A buckle comprising two assembled halves, the buckle being separable into two portions, one portion comprising a receiving part of one half having on its upper surface a rim having a cut-away portion, and a fitted part of the opposite half, said receiving and fitted part being joined by a throat, and the second portion comprising a receiving part adapted to receive said fitted part and having on its upper surface a rim, and on its lower surface a cut-away portion, a second fitted part adapted to be mounted in the first mentioned receiving part, but connected to the receiving part of the second half by a throat, and means whereby the two portions may be assembled together to form the complete buckle assembly with the two throats in the respective cut-away portions.

4. A buckle comprising two assembled halves, the buckle being separable into two portions, one portion comprising a receiving part of one half and a fitted part of the opposite half, the receiving part having on its upper surface a rim having a cut-away portion, said receiving and fitted part being joined by a throat, and the second portion comprising a receiving part adapted to receive said fitted part and having on its upper surface a rim, and a second fitted part adapted to be mounted in the first mentioned receiving part but connected to the receiving part of the second half by a throat, the throat carrying a raised portion adapted when in assembled position to fit into the cut-away portion of the rim of the first mentioned portion to complete said rim, and means whereby the two portions may be assembled together.

5. A buckle having two separable members, one of said members comprising a mounting frame having a rim surrounding a depressed portion, the rim being cut away at one point, a jewel carrier, and a throat connecting the frame and carrier, and the second of said members comprising a mounting frame having a rim surrounding a depressed portion, a jewel carrier, and a throat connecting the frame and carrier, a cut away portion beneath the second member and adjacent the throat thereof, an opening in the second member across the widest part of the depressed part thereof, the jewel carrier of the first member being adapted to be inserted in the opening in the second member so as to seat said jewel carrier in the depression of the second member, the same movement seating the jewel carrier of the second member in the depression in the first member, the throats

of said members fitting in the respective cut away portions.

6. A buckle having two separable members, one of said members comprising a mounting frame, a jewel carrier, and a connection between the frame and carrier, the second of said members comprising a mounting frame, a jewel carrier, and a connection between its frame and carrier, each mounting frame having a portion encompassing the jewel carrier of the opposite member, and means including an opening through one of said members whereby the two members may be assembled together to form the complete buckle assembly with the jewel carriers in the respective mounting frames and with the two jewel carriers on the same side when the buckle is assembled.

7. A buckle having two separable members, one of said members comprising a mounting frame, and a jewel carrier connected thereto, the second of said members comprising a mounting frame, a jewel carrier connected thereto, said second jewel carrier having a rounded portion, the first of said members having an opening through its mounting frame, the opening being semi-circular in shape, the jewel carrier of the second member being inserted through said opening so as to seat the jewel carrier in the mounting frame of the first member, the rounded portion of the jewel carrier passing into its mounted position through the semi-circular opening, the same movement seating the other jewel carrier in the other mounting frame.

8. A buckle adapted to be attached to material upon which it is to be used and comprising two separable members each having a frame and a mounted element, a mounting stirrup on each member, and means whereby the completed buckle is formed by assembling said elements in said frames so as to locate the mounted elements on the upper side of said buckle when the buckle is attached to the material.

9. A buckle adapted to be attached to material upon which it is to be used and comprising two separable members each having a frame and a mounted element, one of said elements carrying a portion of the frame of the other member, a mounting stirrup on each member, and means whereby the completed buckle is formed by assembling said elements in said frames and with the said portion completing its frame and so as to locate the mounted elements on the upper side of said buckle when the buckle is attached to the material.

10. A buckle having two separable members, each member comprising a frame having connected alongside thereof an element to be mounted in a frame, the element of one member being mounted in the frame of the other member and vice versa when the buckle

is assembled, a slot through one of said members communicating with its frame, the element of the opposite member being passed through the slot from the rear in order to assemble the two members together and position the elements in their respective frames.

5 In testimony whereof I affix my signature.

ARTHUR WILLIAM NAUS.
